(57) **CLAIM**

The ornamental design for a vehicle rear seat, as shown and
described.

DESCRIPTION

FIG. 1 is a top front right perspective view of a first
embodiment of a vehicle rear seat;

FIG. 2 is a bottom front right perspective view of the first
embodiment of the vehicle rear seat;

FIG. 3 is a top rear right perspective view of the first
embodiment of the vehicle rear seat;

FIG. 4 is a front elevational view of the first embodiment of
the vehicle rear seat;

FIG. 5 is a rear elevational view of the first embodiment of
the vehicle rear seat;

FIG. 6 is a right side elevational view of the first embodiment
of the vehicle rear seat;

FIG. 7 is a left side elevational view of the first embodiment
of the vehicle rear seat;

FIG. 8 is a top plan view of the first embodiment of the
vehicle rear seat;

FIG. 9 is a top front right perspective view of a second
embodiment of the vehicle rear seat;

FIG. 10 is a bottom front right perspective view of the second
embodiment of the vehicle rear seat;

FIG. 11 is a top rear right perspective view of the second
embodiment of the vehicle rear seat;

FIG. 12 is a front elevational view of the second embodiment
of the vehicle rear seat;

FIG. 13 is a rear elevational view of the second embodiment
of the vehicle rear seat;

FIG. 14 is a right side elevational view of the second
embodiment of the vehicle rear seat;

(Continued)

FIG. 15 is a left side elevational view of the second embodiment of the vehicle rear seat; and,
 FIG. 16 is a top plan view of the second embodiment of the vehicle rear seat.

The broken lines define the bounds of the claim. The broken lines and the lightened portions of the article shown inside the broken lines form no part of the claimed design.
